CLAIM

The ornamental design for a film changing bag, as shown and described.

DESCRIPTION

FIG. 1 is a top, front perspective view of a film changing bag showing my new design;

FIG. 2 is a front elevational view thereof;

FIG. 3 is a rear elevational view thereof;

FIG. 4 is a top plan view thereof, the bottom plan view being substantially identical;

FIG. 5 is a side elevational view thereof; and,

FIG. 6 is an opposite side elevation view thereof of that shown in FIG. 5.
